MULTIPLE VENT PLUG ASSEMBLY FOR STORAGE BATTERIES

Jerome Louis Smentek, Milwaukee, and John Bernard Mohr, Port Washington, Wis., assignors to Globe-Union Inc., Milwaukee, Wis., a corporation of Delaware

Filed Oct. 9, 1968, Ser. No. 13,892

Term of patent 14 years

Int. Cl. D13—02

U.S. Cl. D26—6

FIG. 2

FIG. 4

FIG. 3

FIG. 1

FIG. 1 is a perspective view of a multiple vent plug assembly for storage batteries incorporating our new design;

FIG. 2 is a top plan view;

FIG. 3 is a side elevation view; and

FIG. 4 is an end elevation view.

The broken line disclosure of representative indicia is for illustrative purposes only.

We claim:

The ornamental design for a multiple vent plug assembly for storage batteries, as shown and described.
